HEAT EXCHANGER

Walter Gustav Noack, Baden, Switzerland, assignor to Aktiengesellschaft Brown, Boveri & Cie, Baden, Switzerland, a joint-stock company

Application February 3, 1939, Serial No. 254,512
In Germany February 7, 1938

5 Claims. (Cl. 263—19)

In recent years metal alloys have been made available which are capable of withstanding high temperatures. By the use of such alloys it is now possible to replace heat exchangers, such as 5 hot blast heaters made of refractory ceramic material and generally designed to operate intermittently, by metallic regenerators or recuperators designed to operate continuously. These 10 alloys, however, do not permit the use of gases at the highest temperatures attainable by the combustion of fuel with a slight excess of air. The temperature of the hot combustion gases entering the heat exchanger must be lowered somewhat, for instance by burning the fuel with 15 a large excess of air which of course lowers the heat economy of the whole process, or by using the combustion gases at their highest temperature for some other purpose, for instance for the generation of steam. The generation of steam 20 sometimes is inconvenient and the use of a large excess of air in the combustion is uneconomical because the large volume of waste gases carry away heat. It is desirable therefore and is an object of the present invention to provide a system and a method of operating it whereby the 25 temperature of the gases entering the heat exchanger is lowered to the desired extent without the necessity for using a large excess of air in the combustion of the fuel or generating steam or 30 otherwise utilizing the gases at their highest temperature.

According to the present invention the hot gases, e. g., combustion gases, before entering the heat regenerator or recuperator are mixed 35 with heating gas which has already passed through the regenerator and given up part of its heat content. The temperature of the hot gases is thus lowered to the desired extent without the heat loss incident to burning the fuel 40 with a large excess of air and without generating steam or cooling the combustion gases in some other manner which may be inconvenient or uneconomical. This expedient solves the principal problem involved in the use of metals or 45 alloys in heat regenerators or recuperators. Another problem, however, is the high cost of the metal or alloy used in the construction of the device. In order to reduce the size and cost of the recuperator one may resort to passing the 50 gases at high velocity. However, if the heat exchange surfaces were made as small as is possible for the necessary heat transfer when the combustion gases alone were passed at high velocity, the passages in the recuperator would be so small 55 that the recuperator would be difficult to manu-

facture. If, however, the hot combustion gases are mixed with a portion of the gases leaving the recuperator the volume of the mixture is sufficient, even when passed at high velocity, to warrant a construction of the recuperator which is 5 easy to manufacture and still economical in the use of the expensive metal or alloy.

The recuperator may be operated on the Velox principle, i. e., by passing the gases through it not only at high velocity but also at high pressure. Such operation calls for the service of a compressor which may be driven by a gas turbine which in turn may be driven by the hot gases themselves. In this method of operation, in order to avoid too high temperatures in the recuperator it may appear to be desirable to employ a steam boiler of the Velox type in the path 10 of the gases on their way to the recuperator in order to use the heat of the gases at their highest temperature for generating steam. According 15 to the present invention, however, the use of a steam generator for lowering the temperature of the gases on their way to the regenerator or recuperator is avoided by the return of a portion of the gases leaving the recuperator to the 20 stream of gases on their way to the recuperator. Specifically these partially cooled gases may be withdrawn from the stream of gases passing from the recuperator to the gas turbine. At this 25 point the gases are at such a temperature that 30 they may be handled without cooling and their recompression to the pressure of the gases entering the recuperator requires only the small amount of increase in pressure corresponding to the flow resistance of the recuperator. 35

The invention will be more fully understood by reference to the accompanying drawing in which Fig. 1 is a diagrammatic showing of a source of combustion gases, a recuperator and means for returning a portion of the gases leaving the recuperator to the gases entering the same and Fig. 2 is a diagrammatic showing of a system designed for burning the fuel under pressure. 40

In Fig. 1, 1 is a combustion chamber, 2 is the 45 supply of fuel and air to the combustion chamber, 3 is the heat exchanger, for instance a hot blast heater designed as a recuperator, 4 and 5 are the inlet and outlet respectively of the combustion gases into and out of the heat exchanger, 6 and 7 are the inlet and outlet respectively of the gas to be heated by heat exchange with the hot combustion gases, 8 is a motor and 9 a fan driven by motor 8 for returning a portion of the gases leaving the re- 50 55

generator 3 to the combustion chamber 1. The movement of the gases is indicated by arrows. As appears, the stream of gases leaving the regenerator 3 divides and a portion only of it is returned to the combustion chamber for admixture with the hot combustion gases passing to the regenerator while the remainder is discharged to waste or to other means for utilizing it.

10 In Fig. 2 the combustion chamber 1 is operated on the Velox principle with both the air and fuel supplies under pressure. Fuel and air are supplied under pressure by the blowers or pumps 10 and 11. The hot combustion gases from the 15 combustion chamber pass into the second stage heat exchanger 12 as indicated at 4 and pass out at 5. Here the stream is divided, part of it passing to the fan or blower 9 which delivers it to the combustion chamber for admixture with the hot 20 products of combustion thereby producing a gas mixture having a sufficiently lowered temperature to handle in the heat exchanger. The other portion of the gases leaving the second stage heat exchanger passes to the gas turbine 13 and finally 25 through the first stage of the heat exchanger 14. Turbine 13, driven by the waste gases, drives the fans 9, 10 and 11. 15 is an auxiliary motor, e. g., an electric motor which may supplement the turbine 13. The gases to be heated enter the first 30 stage heat exchanger 14 at 6 and then pass to the second stage heat exchanger 12 and are delivered therefrom at 7.

The temperature of the gas delivered to the heat exchanger may be varied at will without loss 35 of efficiency. When the amount of gas in circulation is increased, its speed is increased and the heat transfer is thereby increased, the heat transfer surface remaining constant. The increased heat transfer compensates for the lower 40 temperature of the gas passing through the regenerator.

The great advantage of the method of operation described is that it leaves the combustion chamber operation entirely independent of the temperature 45 limitations of the metallic heat exchanger and permits the combustion of the fuel at maximum efficiency. The gases returned to the combustion chamber from the regenerator may even serve to cool the walls of the combustion chamber and thus lengthen its life.

50 The invention is of course applicable to any hot gases from which heat is to be recovered and with respect to which a lowering of their temperature and an increase in their volume is desirable.

55 I claim:

1. Apparatus for heat exchange comprising a source of hot heating gases under high pressure, a metallic heat exchanger, means for delivering the hot heating gases from the source thereof

through the heat exchanger, means for passing gases to be heated through the heat exchanger and means for delivering at least a part of the heating gases leaving the heat exchanger into the stream of hot heating gases on their way from 5 said source to the heat exchanger.

2. Apparatus as defined in claim 1 comprising a combustion chamber, compressors for supplying air and fuel thereto under pressure, a gas turbine, means for delivering a portion of the heating 10 gases from the heat exchanger to said turbine and means connecting said turbine to drive said compressors.

3. Apparatus as defined in claim 1 comprising a combustion chamber designed to be operated 15 under pressure, compressors for supplying fuel and air to said combustion chamber under pressure, a turbine connected to drive said compressors, a gas pump driven by said turbine connected to deliver gases into the hot heating gases produced in the combustion chamber, means for delivering a portion of the heating gases leaving the heat exchanger to said gas pump and means for delivering the remainder of said gases to 20 drive the gas turbine.

4. Apparatus for heat exchange comprising a combustion chamber designed to operate under pressure, compressors for delivering fuel and air to said chamber under pressure, a second stage recuperator having heat transfer walls made of 25 metal, means for passing hot heating gases from the combustion chamber through said second stage recuperator, a gas pump, means for delivering a portion of the heating gases leaving said second stage recuperator to said gas pump, means 30 for delivering said portion of the heating gases from the gas pump into the hot heating gases produced in the combustion chamber, a gas turbine connected to drive said compressors and said gas pump, means for delivering the remainder of the heating gases leaving said second stage recuperator to 35 said turbine, a first stage recuperator, means for delivering said remainder of the heating gases from said turbine to said first stage recuperator, and means for passing gas to be heated through said first stage recuperator and said second stage recuperator.

40 5. Apparatus for heat exchange comprising a high pressure combustion chamber, a heat exchanger having metallic heat transfer walls, means for delivering hot heating gases from said combustion chamber to said heat exchanger and means for delivering a portion of the heating gases after passage through said heat exchanger into contact with the walls of said combustion chamber and then into admixture with the hot heating gases leaving said combustion chamber.
